UNITED STATES PATENT OFFICE.

JAMES B. STANWOOD, OF CINCINNATI, OHIO.

VALVE-GEAR.

SPECIFICATION forming part of Letters Patent No. 533,094, dated January 29, 1895.

Application filed January 19, 1891. Renewed June 28, 1894. Serial No. 516,022. (No model.)

To all whom it may concern:

Be it known that I, JAMES B. STANWOOD, a citizen of the United States, residing at Cincinnati, Ohio, have invented new and useful 5 Improvements in Valve-Gear for Steam-Engines, of which the following is a specification.

My invention relates to steam engines of the class employing two cylinders and operating cranks set at or approximately at right 10 angles. In such engines it has been customary to employ separate valve-operating connections each operated by a separate eccentric; and my invention is an improvement upon engines of this description; and consists of a construction and arrangement of the 15 valve-operating mechanism whereby the distributing valves are driven from the same eccentric. This eccentric may be adjustable upon the main shaft and connected to a centrifugal governor, thus obtaining all the benefits 20 of such device with greater relative accuracy of adjustment with the minimum expense of construction; besides being applicable in many situations where two eccentrics 25 could not be used.

Mechanism embodying my invention is illustrated in the accompanying drawings, in which—

Figure 1, is a plan view of a two-cylinder engine with my improvement applied thereto; and Fig. 2, a side elevation of the eccentric and its immediate connections also exhibiting my improvement.

Referring now to the drawings, A, designates the crank-shaft of the engine; B, B', its cranks; C, C', its cylinders; D, D', its valve- 35 rods; E, the eccentric; and, F, the eccentric yoke.

G, designates a shaft-governor which, as 40 the particular character of such governor is of no material importance here, I have indicated in the plan or edge view only, without constructive details.

The eccentric-yoke, F, is connected in the 45 usual manner by a connecting rod, r, directly to the valve rod, D, its connection with the other valve rod, D', being through intervening mechanism as follows: The eccentric yoke, F, is pivotally connected at a point 50 about forty five degrees (corresponding with the crank positions) distant from its connection with the rod, r, by a link, l, with a crank

arm, a, secured upon the rock shaft, b, which is extended in bearings across the frame or bed of the engine to carry a corresponding 55 crank arm, c, in proper relations with a connecting rod, r, extending to and operating the valve rod, r'. The crank arms, a, c, constitute, with their rock-shaft, b, a "bell-crank" by which the vertical motion of the eccentric 60 yoke, F, is translated into a horizontal reciprocation of the second valve rod, r'.

It will be understood that the connections for the bell-crank with the yoke are to be taken on the yoke at points corresponding 65 with the radial angle separating the cranks, and that the bell-crank is to be formed to a corresponding angle.

It will be readily seen that the single eccentric may be constructed and attached to a 70 centrifugal governor, G, upon the shaft in the usual manner; and that, as the angular advance of one valve-movement over the other, is, by the constructive arrangement of parts a fixed quantity, any shifting of the eccentric 75 by the governor to advance or retard its relative action will affect both valve movements alike; also any increase or diminution of the radius of eccentricity of the "eccentric" will affect both valve-movements alike. 80

Many incidental advantages are to be realized from the invention, such as lessened expense of construction, and maintenance; facility in adjusting the valve movements by adjusting one eccentric; and the facility for 85 introducing governor mechanism and reversing appliances by having to deal with but one valve mover.

I claim as my invention and desire to secure by Letters Patent of the United States— 90

1. In a steam engine having two parallel cylinders and driving connections to cranks set at right angles upon a common shaft, a single eccentric upon the shaft; a valve rod from one of the distributing valves connecting directly with the eccentric strap; a valve rod from the other distributing valve; a bell crank pivoted to the engine frame and connecting at one end directly to the second valve rod; and at the other to the said eccentric 95 strap by means of a link, substantially as set forth.

2. In a two-cylinder engine operating a common shaft by means of cranks set at or

approximately at right angles upon a common shaft, a distribution valve for each cylinder; a single adjustable eccentric upon the shaft; driving connections between each distribution valve and said eccentric; and a centrifugal governor upon the shaft controlling the position of said eccentric, substantially as set forth.

3. In a steam engine of the type described, having two parallel cylinders, driving cranks set at right angles and distribution valves arranged between the cylinders; a single valve-moving eccentric on the shaft; parallel valve rods extending toward the shaft; a strap upon the eccentric connecting by means of a yoke rigidly and directly to one of said valve rods; a bell crank pivoted to the frame, so as to project one free arm in front of the eccentric

and connect directly with the second valve rod and the other beneath the eccentric and connect thence vertically with the eccentric strap by means of a link, substantially as set forth.

4. The combination in the two cylinder steam engine of the type indicated, of the eccentric E; strap F; valve-connecting rods r, r'; bell crank a c; and link l, arranged and operating as set forth.

In testimony whereof I have hereunto set my hand in the presence of two subscribing witnesses.

JAMES B. STANWOOD.
